UNITED STATES PATENT OFFICE.

MARIA J. MCQUEENEY, OF NEW HAVEN, CONNECTICUT.

ARCH SUPPORT.

Application filed October 16, 1923. Serial No. 668,906.

To all whom it may concern:

Be it known that I, MARIA J. MCQUEENEY, a citizen of the United States, residing at New Haven, in the county of New Haven and State of Connecticut, have invented a new and useful Improvement in Arch Supports; and I do hereby declare the following, when taken in connection with the accompanying drawings and the characters of reference marked thereon, to be a full, clear, and exact description of the same, and which said drawings constitute part of this application, and represent, in—

Fig. 1 a plan view of an arch-support constructed in accordance with my invention.

Fig. 2 a sectional view on the line 2—2 of Fig. 1.

Fig. 3 a view thereof in front elevation, with the lateral extensions, or positioning-flaps, of its body-member shown by broken lines as turned upward as in use.

My invention relates to an improvement in arch-supports for footwear, the object being to provide, at a low cost for manufacture, a simple, efficient, convenient, non-metallic, adjustable support, providing a high degree of comfort and adapted to be readily adjusted in height by the user, to meet the individual requirements of his or her foot-conformation.

With these ends in view, my invention consists in an arch-support having certain details of construction as will be hereinafter described and particularly pointed out in the claim.

In carrying out my invention, as herein shown, I employ an upper or body-member 10, oblong in general form, preferably having its forward and rear edges curved and having lateral extensions 11 and 12, which are turned upward in use, as indicated by broken lines in Fig. 3, so as to form positioning-flaps which embrace the arch of the foot and laterally support it to some extent. To the under-face of this body-member I secure a shorter secondary or lower member 13 by lines of stitching 14, parallel with each other and parallel with the axis of the foot, its edges 15 being skived or reduced in thickness, so as to merge into the lower face of the body-member, as clearly shown in Fig. 3. A pocket 16, opening forwardly and rearwardly, is thus formed between the two members, for the reception of a plurality of leather shims 17, 18, 19, 20, 21, 22, 23

and 24, diminishing in size from the uppermost to the lowermost, and, as shown, having the general outline of an oyster. The number of these shims may be varied, as well as their outline, the object being to provide each arch-support with a sufficient number of them to enable the user to build up the support according to the requirements of his or her foot-conformation, as determined by the trials of the arch-support in the shoe. All of the parts mentioned are preferably made of a good grade of leather, but the use of leather is not imperative, as some other flexible, non-metallic material might answer the same purpose.

When these shims are in place, they extend forwardly, out of the pocket 16, as shown in Fig. 1, and the conformation of their forward ends will be found conformable to the foot. The user may interchange them, or even cut them, according to his or her needs, as, for instance, if the sole of the foot has callouses or bunions.

It is to be particularly noted that my improved arch-support is heelless in the sense that it does not extend rearward under the heel, whereas, arch-supports, in general, extend under the heel, and so exert a constant tendency to throw the foot forward and crowd the toes into the point of the shoe, which is very objectionable. This tendency is entirely overcome in my improved arch-support, by making it heelless and providing it with a sufficient number of shims to support the foot under the arch, whereby the foot is prevented from crowding forward. When the foot is thrown forward, as with the arch-supports of the prior art, a longer shoe must be worn than with my improved arch-support, which also provides a high degree of comfort, is very efficient in supporting the arch of the foot, and has none of the harshness of metal supports. Such a support may be worn for hours without producing pain or fatigue.

I claim:

As a new article of manufacture, an arch-support for footwear, having a flexible body-member, the major axis of which extends at a right angle to the axis of the shoe in which it is to be worn and the respective ends of which form relatively short positioning-flaps which are turned upwardly when the support is in place in the shoe, a flexible lower-member having its edges fastened to the lower face of the said body-

member by parallel lines of stitching and forming; in conjunction with the middle portion of the said body-member, a forwardly and rearwardly opening pocket, and
5 a plurality of shims superimposed one upon the other, each wider at one end than at the other and decreasing in size from the top to the bottom of the group, both in length and width, the said shims being adapted to
10 be inserted into the said pocket from the forward end thereof, and to project for-

wardly therefrom in position to provide a support for the arch of the foot, and being removable and replaceable each independently of the other.

15

In testimony whereof, I have signed this specification in the presence of two subscribing witnesses.

MARIA J. MCQUEENEY.
